Patented Dec. 13, 1921.

UNITED STATES PATENT OFFICE.

FREDERICK GEORGE CHAMBERLIN, OF NORFOLK, ENGLAND.

LEGGING.

1,399,929.

Specification of Letters Patent. Patented Dec. 13, 1921.

Application filed August 30, 1920. Serial No. 406,978.

To all whom it may concern:

Be it known that I, FREDERICK GEORGE CHAMBERLIN, a subject of the King of England, residing in Norfolk, England, have invented certain new and useful Improvements in Leggings, of which the following is a specification.

This invention is for improvements in or relating to leggings or the like and has for its object to provide a legging wherein the overlapping edge shall lie closely down upon the other edge without the aid of a multiplicity of fastenings such as are at present usually employed. As is well known, the band which is sometimes used at the bottom of the legging and the strap and buckle at the top are not sufficient to keep the overlapping edge from gaping, and therefore lace fastenings and other devices are used between these two main fastening means.

According to the present invention, the legging is provided at the bottom with an overlapping band which encircles it and is fastened, for example by a strap and buckle, but this band is characterized by a tie-piece which fills in the corner between the top edge of the band and the overlapping edge of the legging. This tie-piece may be made of thinner material than is the band or legging and is sufficiently full at the free edge to lie closely against the exterior of the legging where the same is enlarged or shaped to fit the leg.

The legging may be of woven material or it may be of leather, the material of which it is made not being pertinent to the present invention.

In the accompanying drawings, which illustrate one preferred form of the invention—

Figure 1 shows the legging as applied to the leg of a wearer,

Fig. 2 shows, in perspective, the legging removed and opened out, and

Fig. 3 illustrates a portion of one edge of the legging together with the overlapping or throw-over band the parts being drawn as though lying flat to show the shaping of the band.

To the lower end of the overlapping edge 1 of the legging is secured the overlapping band 2 which, as shown in Fig. 1, encircles, when in use, the lower end of the legging and is fastened by means of the strap 3 and buckle 4. A triangular tie-piece 5, which

extends approximately to the top of the legging, is secured to the overlapping edge 1 and to the adjacent portion of the top edge of the band 2 to fill in the corner between those two parts. When in use the part 5 laps partially around the legging, and its lower corner, remote from the edge 1, extends around the legging to a point about at or preferably slightly short of the back center-line of the legging.

Alternatively the legging corner filling-piece 5 and band 2 may be all formed from a single piece of material or the strap 2 and the piece 5 may be formed in one piece and secured to the legging.

At the other (top) end a fastening strap on the free edge of the legging engages a buckle 7 near the opposite edge of the legging but inset somewhat therefrom to fasten the top together. The strap 6 may be formed separately from but secured to the legging, or it may be formed integral with the material of the overlapping edge thereof.

Fig. 3 indicates the shape to be given to the band 2 in order that it may lap as uniformly tightly as possible over its whole width around the lower part of the legging. The top and bottom edges may, for this purpose, in one form of the invention be curved as concentric arcs of circles the center of which lies approximately on an imaginary line extended downwardly from the overlapping edge 1 and the end portion of the band, where it is secured to the edge 1, is preferably slightly tapered to a smaller width than is its major portion, conveniently by chamfering the top edge.

Some such curvature of the band is preferable in order to accommodate for the difference in circumferential measurements of the legging at positions in its length corresponding with the upper and lower edges of the band. If desired, the upper and lower margins of the band may be rolled or otherwise treated to slacken them slightly as compared with the central portion so that the latter may grip tightly into the narrow portion of the ankle, while the two edges also grip tightly around their appropriate parts. Alternately the band may be formed without slackening the marginal portions, in which case they will, with most materials commonly used, stretch in use to the required degree.

It is preferred that the length of the band

- 2 be such that its free end, when wrapped around the legging, terminates immediately below and in line with the lower corner of the part 5 where the latter joins the band 2.
- 5 It is found that a legging made in this manner need have no further fastening other than the bottom band and top strap, as the tie-piece which fills in the angle between the top of the band and the overlapping edge of 10 the legging keeps the said overlapping edge well down upon the opposite edge without any intermediate fastenings.
- What I claim as my invention and desire to secure by Letters Patent is:—
- 15 1. A legging or the like having in combination means to fasten the top corner of the overlapping edge of the legging, an encircling strip of substantially uniform width at the bottom, and means to fasten the free end 20 of said strip after it has been wrapped around the lower end of the legging, the overlapping edge of the latter being so formed as to extend diagonally from its upper end to the top edge of said encircling 25 strip and the length of the strip beyond its connection with the said diagonally extended overlapping edge being such as to wrap around the lower portion of the legging to an appreciable extent, substantially as de- 30 scribed.
2. A legging or the like having in combination means to fasten the top corner of the overlapping edge of the legging, an encircling strip of substantially uniform width at 35 the bottom, and means to fasten the free end of said strip after it has been wrapped around the lower end of the legging, the overlapping edge of the latter being so formed as to extend diagonally from its upper 40 end to the top edge of said encircling strip and the length of the strip beyond its connection with said diagonally extended overlapping edge being such as to wrap approximately once completely around the leg- 45 ging, substantially as described.
3. A legging or the like having in combination means to fasten the top corner of the overlapping edge of the legging, an encircling strip of substantially uniform width 50 at the bottom, and means to fasten the free end of said strip after it has been wrapped around the lower end of the legging, the overlapping edge of the latter being so formed as to extend diagonally from its upper 55 end to a position at the top edge of said strip such that its junction with the strip, when the legging is in use, is at a point approximately on the back center line of the legging, and the length of the strip, beyond 60 its connection with the said diagonally extended overlapping edge, being such as to wrap around the lower portion of the legging to an appreciable extent, substantially as described.
- 65 4. A legging or the like having in combination means to fasten the top corner of the overlapping edge of the legging, an encircling strip of substantially uniform width at the bottom, and means to fasten the free end of said strip after it has been wrapped around the lower end of the legging, the overlapping edge of the latter being so formed as to extend diagonally from its upper end to the top edge of said encircling strip and the length of the strip, beyond its connection with the said diagonally extended overlapping edge, being such as to wrap around the lower portion of the legging to an appreciable extent, substantially as described.
7. A legging or the like having in combination means to fasten the top corner of the overlapping edge of the legging, a curved encircling strip of substantially uniform width at the bottom, and means to fasten the free end of said strip after it has been wrapped around the lower end of the legging, the overlapping edge of the latter being so formed as to extend diagonally from its upper end to the top edge of said encircling strip and the length of the strip, beyond its connection with the said diagonally extended overlapping edge, being such as to wrap around the lower portion of the legging to an appreciable extent, substantially as described.
8. A legging or the like having in combination means to fasten the top corner of the overlapping edge of the legging, a curved encircling strip which is at the bottom of the

legging and is of substantially uniform width over the major portion of its length from its free end but is tapered slightly in the region of and toward its line of connection with the legging, the overlapping edge of the latter being so formed as to extend diagonally from its upper end to the top edge of said encircling strip, and the length of the strip, beyond its connection with the said diagonally extended overlapping edge, being such as to wrap around the lower portion of the legging to an appreciable extent, substantially as described.

9. A legging or the like having in combination means to fasten the top corner of the overlapping edge of the legging, an encircling strip of substantially uniform width which is at the bottom of the legging and is curved downwardly toward its free end, and means to fasten the free end of said strip after it has been wrapped around the lower end of the legging, the overlapping edge of the latter being so formed as to extend diagonally from its upper end to the top edge of said encircling strip, and the length of the strip, beyond its connection with the said diagonally extended overlapping edge, being such as to wrap around the lower portion of the legging to an appreciable extent, substantially as described.

10. In a legging or the like having in combination means to fasten the top corner of the overlapping edge of the legging, an encircling strip of substantially uniform width which is at the bottom of the legging and is curved so that the major portion of its upper and lower edges both lie on approximately concentric arcs of circles struck from a center which lies on an imaginary line extended downwardly from the overlapping edge of the legging, and means to fasten the free end of said strip after it has been wrapped around the lower end of the legging, the overlapping edge of the latter being so formed as to extend diagonally from its upper end to the top edge of said encircling strip and the length of the strip, beyond its connection with the said diagonally extended overlapping edge, being such as to wrap around the lower portion of the legging to an appreciable extent, substantially as described.

lower portion of the legging to an appreciable extent, substantially as described. 30

10. In a legging or the like having in combination means to fasten the top corner of the overlapping edge of the legging, an encircling strip of substantially uniform width which is at the bottom of the legging 35 and is curved so that the major portion of its upper and lower edges both lie on approximately concentric arcs of circles struck from a center which lies on an imaginary line extended downwardly from the overlapping edge of the legging, and means to fasten the free end of said strip after it has been wrapped around the lower end of the legging, the overlapping edge of the latter being so formed as to extend diagonally from its upper end to the top edge of the strip, beyond its connection with the said diagonally extended overlapping edge, being such as to wrap around the lower portion of the legging to an appreciable extent, substantially as described. 40

45 In testimony whereof, I affix my signature.

FREDERICK GEORGE CHAMBERLIN.
